William H. Penseyres Inventor.
By James Langstroth Attorney.

UNITED STATES PATENT OFFICE.

WILLIAM H. PENSEYRES, OF BUFFALO, NEW YORK.

BICYCLE CRANK-SHAFT.

SPECIFICATION forming part of Letters Patent No. 619,499, dated February 14, 1899.

Application filed December 18, 1897. Serial No. 662,391. (No model.)

To all whom it may concern:

Be it known that I, WILLIAM H. PENSEYRES, a citizen of the United States, residing at Buffalo, in the county of Erie and State of New York, have invented certain new and useful Improvements in Bicycle Crank-Shafts, of which the following is a specification.

My invention relates to a two-piece crank-shaft, its antifriction bearing mechanism, and the means employed for locking the two divisions of the shaft together; and the object is to lessen the number of parts required, simplify and cheapen the construction thereof, and to produce a device which can be easily and quickly operated to assemble or disengage the two sections to or from each other.

It also relates to certain details of construction, all of which will be fully and clearly hereinafter described and claimed, reference being had to the accompanying drawings, in which—

Figure 1 represents a vertical central section through the crank-hanger, sprocket-wheel, bearings, ball-retainers, and dust-protectors. Fig. 2 represents an end elevation of the crank-hanger, showing also portions of the frame-tubes and the cranks.

Referring to the drawings for the details of construction, in which like numerals represent like or duplicate parts, I designate the crank-hanger, which is of the usual barrel type, by the numeral 1. It is provided with the usual lugs 2 for attachment to the frame-tube, the interior screw-threaded end portions 3 for receiving the bearing-cases, the slots 4, and the lugs or ears 5, which are provided with screw-threaded openings to receive and retain the bolts 6.

The bearing-cases 7, which are duplicates of each other and are therefore designated by the same numeral, are provided with peripheral screw-threads adapted to engage with the screw-threads in the end portions 3 and the flanges 8, which extend peripherally therefrom, near the outer edges, and form shoulders against which the outer edges of the crank abut, thus limiting the entrance of the bearing-cases in the ends thereof.

The divisional crank-shaft comprises the two separable portions 9 and 10, which differ in certain details, as will appear farther on. They are provided with inner reduced end

portions, which when interlocked together form a shaft of substantially the same circumference throughout, and with cranks 11 and 12, which are bent therefrom at substantially right angles.

The shaft portion 9, with its crank 11, I preferably designate as the "sprocket-wheel-supporting" portion, and the shaft portion 10, with its crank 12, as the "locking-device-supporting" portion.

The outer end of the shaft portion 9 is provided with an enlarged peripheral screw-threaded portion 13, which at the juncture 65 with the crank merges into the enlarged base portion 14, and the crank 11 is enlarged for a short distance from its juncture with the shaft portion 9 to provide a base 15, which is provided with a screw-threaded opening 16, 70 the purpose of which will appear farther on.

The tubular sleeve 17, into which the shaft portions are fitted, is provided at one end with a flange 18, and the sprocket-wheel 19 is provided with an interior screw-thread 20, adapted to engage with the enlarged screw-threaded portion 13 on the shaft. A short tubular portion 21, having a smooth-surfaced opening of less circumference than the screw-threaded opening 20, extends from the inner side of 80 the sprocket, terminating in the interiorly-projecting flange 22.

To assemble the several parts of the sprocket-wheel-supporting portion, the shaft portion 9 is fitted into the flanged end of the 85 tubular sleeve 17 and the sprocket-wheel 19 slipped over the sleeve and firmly secured upon the screw-threaded portion 13, the flange 22 on the sprocket abutting against the flange 18 on the sleeve 17, thereby locking the sleeve 90 to the shaft portion. The cone 26^a is then slipped over the sleeve and seated against the inner face of the flange 22 of the sprocket.

The cone 26^a may be formed with a plain-surfaced interior, as shown in Fig. 1, and simply seat against the sprocket-flange, or the flanged end of the sleeve may be enlarged and screw-threaded and the interior of the cone correspondingly screw-threaded.

To prevent rotation independent of its shaft 100 and also additionally secure the sprocket thereto, a screw 23 is passed through an opening in the sprocket and into the opening 16 in the crank.

The shaft portion 10 enlarges slightly before its juncture with the crank 22 into the portion 24, the inner edge of which forms a shoulder against which the unflanged edge 5 of the tubular sleeve abuts.

The enlarged portion 24 is provided with a peripheral groove 25, and the cone 26 has a corresponding interior groove 27. The purpose of these grooves is to provide a runway 10 for a series of balls 28, which are introduced therein through an opening in the cone, a screw-plug 29 being provided to close said opening when required.

The unflanged end of the tubular sleeve is 15 screw-threaded upon its exterior, and the cone 26 has an interior screw-thread adapted to engage with the screw-thread upon the sleeve.

The protruding face of the cone has one or 20 more openings 30 to receive the pins of a locking-tool; but, if desired, it may be formed square or hexagonal and an ordinary wrench used in lieu thereof.

The usual antifriction-balls 31 are interposed between the cones and bearing-cases, 25 and the bearings are also provided with the ball-retainers 32 and felt washers 33.

The device is assembled as follows: The bearing-cases are screwed into the ends of the 30 crank-hanger, the balls 31 introduced, and the ball-retainers and felt washers properly placed thereon. The sprocket-supporting portion is assembled as heretofore explained and the end of the sleeve passed into the 35 hanger. The cone-supporting portion being assembled as heretofore explained it is introduced through the other side of the hanger and the end of the shaft portion is slipped into the sleeve. The cone is now revolved by 40 means of a locking-tool and secured upon the sleeve and the two shaft portions are firmly interlocked with each other. The cone is then rigidly locked upon the shaft portion by screwing the plug 29 firmly against or be- 45 tween two of the balls, thus jamming them and preventing their rotation.

I claim as my invention—

1. In a bicycle, the combination of a two-part shaft, one portion having a peripheral 50 screw-threaded enlargement, a tubular sleeve

having a flange at one end, a sprocket having a central screw-threaded opening adapted to screw upon the screw-threaded enlargement, and provided with a portion fitting over said flange and means for locking the shaft parts 55 and the sleeve together, as set forth.

2. A bicycle crank-hanger and mechanism therefor, comprising the hanger having the ends screw-threaded, bearing-cases provided with peripheral screw-threads engaging with 60 in the screw-threaded ends of the crank-hanger, means for locking said bearing-cases at any point to which they may be adjusted, a two-part shaft having interlocking ends, one portion being provided with an enlargement 65 having a peripheral screw-thread and the other portion with an enlargement having a peripheral groove, a tubular sleeve provided at one end with a raised flange and at the other with a peripheral screw-thread, a 70 sprocket having a central screw-threaded opening adapted to be screwed upon the screw-threaded enlargement of the first shaft portion, and provided with an inner offset portion lapping over the flange on the sleeve 75 thus securing the sleeve to the said shaft portion, an unadjustable cone seated against the inner face of said sprocket portion, a cone provided with an interior groove corresponding to the groove on the other shaft portion 80 with a screw-threaded opening extending from said groove through the side of the cone and an interior screw-thread adapted to engage with the screw-threaded end of the sleeve, a series of balls adapted to be dropped through 85 the screw-threaded opening in the cone side and interposed between the two grooves to provide for the easy rotation of the cone upon the shaft portion and prevent longitudinal movement thereon, a screw adapted to be 90 screwed into said screw-threaded opening and upon the balls for locking said cone to prevent rotation, and a series of antifriction-balls interposed between the cones and the bearing-cases, as set forth.

WILLIAM H. PENSEYRES.
